DOOR HOOK

Homer Earl Algeo, Carrollton, Ohio

Application September 8, 1936, Serial No. 99,847

1 Claim. (Cl. 292—95)

This invention relates broadly to door holders and more particularly to a holder in the form of a hook to be secured to screen doors or other closure members and so constructed and arranged 5 that when not in use it will automatically fold over to a position close to the door whereas when in use, it may swing to a position for engaging the eye of a keeper bolt or the like mounted on the door jamb for securing the door in closed position.

10 The invention, together with its objects and advantages will be best understood from a study of the following description taken in connection with the accompanying drawing wherein:—

Figure 1 is an elevational view illustrating the 15 application of the door hook and showing the same as used for securing the door in closed position.

Fig. 2 is a view somewhat similar to Fig. 1 and showing the position of the hook when not in use.

20 Fig. 3 is a fragmentary detail sectional view showing the pivot for the hook and

Fig. 4 is a view of a hinge forming part of the invention.

Referring to the drawing more in detail, it 25 will be seen that in accordance with the present invention there is provided an attaching hinge for the hook 5, and the hinge is indicated generally by the reference numeral 6.

The hinge 6 in accordance with the present invention, 30 comprises a hinge leaf or plate 7 provided with holes or the like 8, through the medium of which and screws or other fastening elements 9 the plate 7 is secured to the frame 10 of a screen door or similar closure fragmentarily shown in 35 the drawing, and indicated generally by the reference numeral 11.

At one edge thereof, the plate 7 is provided with integral vertically spaced sleeves 12 which accommodate the hinge pin 13.

40 Further, the hinge includes a plate or leaf 14 which is materially smaller than the plate or leaf 7 and is provided at one end with vertically spaced sleeves 15 accommodated between and alining with the sleeves 12 in a manner to receive the hinge pin 13 whereby the leaf or plate 14 is hinged to the leaf or plate 7.

Disposed about the hinge pin 13 between the leaves 15 of hinge plate 14 is a coiled spring 16 45 one end of which engages behind the plate 7 as at 16a and the relatively opposite end of which engages behind the plate 14 as at 16b. Thus it will be seen that the spring 16 tends to normally urge the plate 14 into the folded position relative to 50 the plate 7 illustrated in Fig. 4.

The hook 5 which is of conventional structure has the eye equipped end thereof pivoted to the plate 14 through the medium of a rivet or the like 17 as clearly shown in Fig. 3.

To limit vertical swinging movement of the 5 hook 5 in either of two directions, plate 14 is provided at its upper and lower edges with laterally directed, integral stop lugs 18.

From the above, it will be seen that in using the device, when the door is closed and it is desired to secure the door in closed position through the medium of the hook device, the hinge plate 14 together with the hook 5 is swung around from the position shown in Fig. 2 to the position shown in Fig. 1 and the hook 5 engaged with the eye of 15 the keeper bolt 19 suitably provided on the jamb portion of the usual frame 20 around the door opening in the building.

When it is desired to unhook the door, the hook 5 is raised upwardly out of engagement with the 20 eye of the keeper bolt 19, and under action of spring 16 the leaf plate 14 will be caused to swing to the position shown in Fig. 2, and the hook 5 will drop down to the tendant position 25 also shown in Fig. 2.

It will also be observed that with a hook device embodying the features of the present invention, the hook 5, when released, will immediately be moved to a position which would preclude an unintended or accidental engagement of the hook 5 with the keeper bolt 19 when the door 11 is in 30 closed position.

Having thus described the invention, what is 35 claimed as new is:—

A closure fastener comprising a flat hinge plate adapted to be secured to a closure and provided at one edge with a pair of spaced alined sleeves, a second flat hinge plate materially smaller than the first hinge plate and provided at one edge 40 with a pair of spaced sleeves disposed between and alining with the first mentioned sleeves, a hinge pin extending through the alined sleeves and connecting the plates in vertical edgewise position, a spring disposed on the hinge pin between the sleeves of the last-mentioned plate and having one end bearing against one side of one of said hinge plates, and a relatively opposite end bearing against one side of the second-mentioned hinge plate for normally urging the latter into 45 folded position relative to the first hinge plate, and a hook pivoted at one end to the surface of said second-mentioned hinge plate.
